UNITED STATES PATENT OFFICE.

JAMES HENRY BRADY, OF LOUISVILLE, KENTUCKY, ASSIGNOR TO PRISCILLA WEAVING ART COMPANY, OF LOUISVILLE, KENTUCKY, A CORPORATION OF KENTUCKY.

ADJUSTABLE FRAME.

1,175,924.

Specification of Letters Patent. Patented Mar. 21, 1916.

Application filed February 23, 1915. Serial No. 9,952.

To all whom it may concern:

Be it known that I, JAMES HENRY BRADY, a citizen of the United States, residing in the city of Louisville, county of Jefferson, 5 and State of Kentucky, have invented a certain new and useful Improvement in Adjustable Frames, of which the following is a specification.

This invention relates to adjustable frames particularly adapted for use in making mats, for household use, though they may be capable of broader application.

An object is the provision of a frame which may be readily assembled and easily 15 adjusted to form rectangles of different dimensions.

A further object is the provision of a frame of the character described, which will be economical in construction and durable 20 in service.

With the foregoing and other objects in view, the invention consists of the novel arrangement and construction of parts illustrated in the accompanying drawing, where- 25 in is set forth an embodiment of the invention, but it is to be understood that such changes and modifications may be resorted to as come within scope of the appended claims.

30 Referring to the drawings wherein similar reference characters designate like parts in the several views; Figure 1, is a plan of a frame assembled to form a rectangle; Fig. 2, a perspective of a portion of one of 35 the members, on an enlarged scale; Fig. 3, a plan of a frame assembled to form a square, and showing the manner of positioning material thereon to form a mat.

Referring now more particularly to the 40 drawings a frame, designated by the reference character —1— comprises a plurality of dentated strips —2—, which may be of any suitable or desirable dimensions. These strips may be constructed of any material 45 suitable for the purpose for which the frames are to be employed. The strips are divided by a plurality of uniformly spaced transverse slots —3— extended in from the upper surface into a series of dentils —4—. 50 A connecting member —5— secured on one side of each strip, by suitable means such as screws —7—, with its upper edge flush

with the upper edge of the strip, extends beyond the end thereof a distance equal to the width of the strip and has a right angled extension —6—, the length of which is slightly greater than the combined width of a slot and a dentil. The width of a connecting member is the same as the depth of a slot 3, and the thickness such that it 60 may be easily placed in any slot of a complementary strip. The frame is assembled by abutting the end of a strip, from which the connecting member extends, against the side of a second strip, and the connector 65 pushed down in a selected slot. The angular extension 6 lies along the far, or outside, of the second strip and effectively secures the first strip against movement in any except a vertical plane. Similarly a 70 third strip is connected to the first, and the second to the third. It is to be observed that any sized frame may be formed by appropriate selection of slots. Indices may be placed in juxtaposition to the slots to 75 facilitate the selection of slots to form desired sizes. It is to be observed that the indices shown on the drawing indicate the size, in inches, that a mat will be if the frame is assembled with the connectors in 80 the corresponding slots.

In making mats with this frame, material of suitable nature, such as cord or tidy cotton, is placed in the slots, being stretched across the frame from side to side, and 85 wound about opposing dentils first in one direction then transversely. When a desired quantity of cord, usually eight strands, has been accumulated in all the slots, the longitudinal strands —9— and the trans- 90 verse strands —10— are tied together at their intersections by suitable means such as knots —11—. When the intersections have all been united the mat may be removed from the frame by slipping the loops 95 off the dentils; the loops may then be cut and will form a fringe for the mat.

It will be observed that on the end of the strip to which the connector is secured, a slot has been omitted. This has been done 100 to provide an extent of cord to form the fringe of a mat. This omission might cause confusion in alining the cord across the frame were it not that the angular projec-

tions 6 from the connectors block what would be the corresponding slot on the opposite strip.

Having thus described my invention so that any one may make and use the same, I claim:

1. A plurality of interchangeable strips adapted to be assembled in rectangular contour with an end of each strip abutting 10 against a side of another strip lying in the same plane therewith, said strips each having a plurality of transverse slots extended in from the upper surface thereof for the reception of work, an L shaped connector 15 attached by one leg to each strip at the abutting end thereof and extended longitudinally therefrom through any slot of the adjoining strip, the other leg lying along the far side of the adjoining strip blocking 20 the entrance to an adjacent slot.
2. A frame comprising a plurality of interchangeable strips each having a plurality of spaced transverse slots extended in from the upper surface thereof for the 25 reception of work, and having an L shaped connector attached to and extending from an end thereof, the width of said connectors being the same as the depth of said slots whereby when the strips are joined by placing 30 the extended leg of a connector in any slot of a complementary strip said strips will lie in the same plane and the lateral

leg of the connector will lie along the far side of the connected complementary strip and close the entrance to an adjacent slot.

3. A frame member comprising a rectilinear strip having a plurality of uniformly spaced transverse slots extended in from the upper surface thereof, and an L shaped connector attached to one end thereof in such relationship thereto that when the attached leg is placed in any slot of a complementary strip said strips will lie in the same plane while the lateral leg lies along the far side of the complementary strip, holding the strips in juxtaposition and blocking the entrance to the slot adjacent to that through which the extended leg is disposed.

4. A frame comprising detachably engaged side members each having a plurality of uniformly spaced slots extended in from the upper surface for the reception of work, a connector attached to each strip near the end thereof and extended longitudinally therefrom, said connectors being insertible in any slot of the complementary strips, and having an angular extension to lie longitudinally along the adjoined strip blocking the entrance to an adjacent slot.

J. HENRY BRADY.
